MACHINE FOR MAKING AND APPLYING
ORNAMENTAL DEVICES

Cesar Bustamante, New York, N. Y.

Application July 9, 1946, Serial No. 682,447

4 Claims. (Cl. 1-2)

1

This invention relates to apparatus for automatically attaching devices to sheet material for the purpose of ornamentation. The ornamentation device may serve as a holder or mounting for an ornamental stone or gem such as a rhinestone, or the ornamentation device may itself constitute the ornamentation, such devices being known in the trade as "nailheads." The ornamentation devices are usually applied to fabric, such as women's dress goods, but they may also be applied to various other materials such, for example, as leather, and it will be understood that the term "fabric" as used herein includes any sheet material which is suitable to receive the ornamentation.

The object of the invention is to provide an improved machine for both fabricating and applying the ornamental devices to the fabric, both of these operations being carried out by the single machine, a single stroke or cycle of operation of such machine serving to stamp out, bend, form and apply the ornamentation device to the fabric, with or without the simultaneous application of an ornamental stone.

The machines which have heretofore been proposed for attaching ornamental devices to fabric, and which have included mechanism for fabricating as well as applying the ornamentation devices, have proved unsatisfactory for one reason or another and have not gone into general use, and the object of the present invention also is to provide an improved machine of this kind which will operate without skipping, which will leave no sharp edges on the ornamental devices exposed to catch the threads of fabric surfaces brought into contact with them during the manufacture of articles of clothing, or otherwise, from the ornamented fabric, and which will fashion the ornamentation devices to a precise predetermined shape.

Such precise fashioning of the devices, where ornamental stones are used, enables the stone not only to be more securely held in position but also imparts a neater appearance to the fabric than is the case with fabric ornamented by the automatic attaching machines heretofore constructed. In decorating fabric with nailheads, the precise fashioning produced by the machine of the present invention results in uniformity and an improved appearance of the exposed portions of the nailheads.

The invention will be understood by considering the accompanying drawings showing, by way of example, one embodiment of the invention. In these drawings,

2

Fig. 1 is a view of the machine in front elevation;

Fig. 2 is a view partly in section and partly in front elevation taken on line 2-2 of Fig. 3 with the mechanism in a different position from either Fig. 1 or Fig. 3;

Fig. 3 is a view partly in side elevation and partly in vertical central section with the mechanism in a different position from either Fig. 1 or Fig. 2;

Fig. 4 is a view in central transverse vertical section drawn to an enlarged scale and showing a portion of the mechanism of the lower central part of Fig. 2, and the position of mechanism corresponding to that figure;

Fig. 5 is a vertical section taken on broken line 5-5 of Fig. 4 and drawn to the same scale as Fig. 4;

Fig. 6 is a fragmentary side view with the parts in a different position than in Fig. 4;

Fig. 7 is a detail horizontal section taken on line 7-7 of Fig. 4;

Fig. 8 is an end view of the reversible carrier shown in Fig. 9;

Fig. 9 is a longitudinal section of the reversible carrier taken on line 9-9 of Fig. 8;

Fig. 10 is an enlarged vertical section of the reversible carrier and its adjacent parts taken on line 10-10 of Fig. 3;

Fig. 11 is a fragmentary view of the parts shown in upper portion of Fig. 10 but in a slightly different position;

Figs. 12 and 13 are respectively a top view and a side view of an ornamentation device in the form of a mounting or holder for a gem such as a rhinestone;

Fig. 14 is a view of the blank before bending the legs and forming;

Figs. 15 and 16 are corresponding and similar views to Figs. 12 and 13 of an ornamentation device in the form of a nail head;

Fig. 17 is a view in side elevation of the lower portion of a punch used in connection with the forming and application to the fabric of the nail head shown in Figs. 15 and 16;

Fig. 18 is a sectional view of a fragment of fabric with a nailhead applied to it; and

Fig. 19 is a detail central vertical section showing a modification of the lower part of the machine.

Referring now to the accompanying drawings, and first to Fig. 3, the machine comprises a frame 1 which may be conveniently made in the form of an iron casting. Frame 1 has a base portion 2 which may serve as a means for attaching sup-

porting legs (not shown), and also table surfaces (not shown) at both the left and right sides as viewed in Fig. 1 to support the fabric being decorated to facilitate the manipulation thereof.

At the top frame 1 is arranged with suitable bearings for a main operating crankshaft 3 having a pulley 4 at its rear end by means of which power for operating the machine is applied. Pulley 4 is arranged to turn loosely on shaft 3 and to be clutched thereto by means of a one-revolution clutch 5 such as is in common use for operating power presses. Clutch 5 is provided with the usual clutching and de-clutching lever 6 which may be controlled through a link 7 attached to a foot pedal (not shown) arranged below at a convenient position for the operator of the machine. The construction of clutch 5 is such that if the foot pedal is depressed only momentarily shaft 3 will make only a single revolution, but if the pedal is depressed continuously shaft 3 will continue to rotate until the pedal is released.

Base 2 of the frame is also provided with bearings to support an auxiliary shaft 8 which is driven at the same speed as main shaft 3 by means of an endless chain 9 passing over sprockets fixed to the respective shafts. Both of shafts 3 and 8 have crank discs fixed at their front ends. Crank 10 on the upper disc operates a vertical reciprocating plunger 11 through a connecting rod 12. Crank 13 on the lower disc operates a lower plunger 14 through a connecting rod 15. The arrangement is such that crank 10 reaches the bottom dead center position at approximately the same time that crank 13 reaches the top dead center position. In other words, the cranks operate in synchronism 180° apart.

Reciprocating plunger 11 slides in bearing apertures 16 and 17 which are spaced one above the other in the upper part of frame 1 at the level of the lower bearing aperture 17. Frame 1 is provided with two integral projecting bosses 18, 19, which have adjacent their ends parallel vertical apertures 19 (Fig. 2). The center of plunger 11 is hollow, having an axial bore to receive the shank 20 of a forming or fashioning punch 21, which is secured in any suitable manner as, for example, by means of a screw 22 (Fig. 2) the head of which is recessed below the surface of the plunger in order not to interfere with the sliding of the plunger in aperture 17.

At a distance below the lower end of plunger 11, and suspended therefrom, there is a carriage indicated generally by numeral 23 (Fig. 2). This carriage (Fig. 5) supports a blanking punch 24 in the form of a sleeve surrounding forming or fashioning punch 21, together with a cooperating blanking die 25 and immediately below it a prong bending die 26 with which the lower end of punch member 21 cooperates, all as will be described in detail later on. Carriage 23 also supports, by means of a pair of side plates 27, 27, a reversible carrier 28 which is pivoted between plates 27 at their lower ends as also will be described in detail further on. Carriage 23 also supports a part of the mechanism for actuating the sleeve type blanking die 24 to be described in detail.

Carriage 23 is composed of two nearly cubical blocks 29, 29 (Figs. 2 and 5), a combined die supporting member and punch guide 30, and plates 27. Guide support 30 is disposed below blocks 29 and serves to support blanking die 25 and bending die 26 which are attached to it by means of screws 31.

Carriage 23 has a reciprocating motion which is imparted to it by plunger 11 although the stroke of the carriage is less than that of plunger 11. With this in view plunger 11 carries at its lower end a cross-head 32 which is held against the lower end of the plunger by an integral enlargement 33 on shank 20 of punch member 21. Cross-head 32 has a U-shaped aperture 34 for the passage of shank 20, in order to facilitate the replacement of punch 21, with one of a different size as may be required in setting up the machine for different kinds of work.

Carriage 23 is supported on cross-head 32 by means of two vertically extending rods 34 which are fixed at their lower ends in blocks 29. They pass through apertures in the opposite ends of cross-head 32 in which they are freely movable, and, above the cross-head, rods 34 are provided with enlarged upward extensions 35, on the upper ends of which are pairs of nuts 36, one locking the other. The enlarged projections 35 terminate at their lower ends in shoulders 37 against which cross-head 32 is urged by means of coil springs 38 surrounding each of rods 34. The combined action of springs 38 and shoulders 37 consequently serves to suspend rods 34 and carriage 23 from cross-head 32 and the lower end of plunger 11.

The stroke of carriage 23 is shorter than that of plunger 11, this being brought about by the structure just described as will be evident from the following. The extensions 35 of rods 34 slide freely in the apertures 19 of bosses 18; also, the apertures in the ends of cross-head 32 have a sliding fit with rods 34, springs 38 being the only agency which tends to maintain shoulders 37 in contact with cross-head 32. It will, therefore, be understood that as plunger 11 moves downward from its uppermost position carriage 23 moves with it until the two pairs of nuts 36 strike the surfaces of bosses 18. This arrests the movement of carriage 23 and occurs slightly in advance of the position of crank 10 shown in Fig. 2.

At the point in the stroke of plunger 11 where nuts 36 contact bosses 18 cross-head 32 begins to move downwardly away from shoulders 37, compressing springs 38. In Fig. 2 this relative movement has just commenced. The downward movement of plunger 11 continues until the lower end of forming or fashioning punch 21 reaches the approximate position shown in Fig. 3. The reason for providing this relative movement between plunger 11 and carriage 23, and the events which occur during such movement will be described below. Prior to this the necessary description of the construction of certain parts will be given.

The various parts composing carriage 23 are assembled as shown more particularly in detail in Figs. 4 and 5. As mentioned above, the blanking and bending dies 25 and 26 are secured to punch guide and die support 30. Support 30 extends the entire width of carriage 23 and is secured to it through the side plates 27 which are provided with dowel pins 39 fixed at their outer ends in plates 27 as shown in Fig. 4. The inner ends of dowel pins 39 fit into holes provided in the opposite sides of die support 30. Side plates 27 also have a similar set of dowel pins 40, the inner ends of which fit into holes in blocks 29 of the carriage. Side plates 27 are secured against the sides of blocks 29 by means of a pair of through-bolts 41.

It was previously mentioned that reversible carrier 28 is pivoted between the lower ends of plates 27. This is done in such a way that by

removing plates 27 carrier 28 can be replaced with another for making and applying ornamentation devices of a different size. For this purpose carrier 28 has at its opposite sides two aligned trunnion recesses to receive a pair of trunnion bearings 42, 43. Trunnion 42 projects from a member 44 which serves as a spacer to align the center of reversible carrier 28 with the center line of punch 21 and plunger 11. Member 44 also has an outer projecting portion 45 which fits within an aperture at the lower end of front plate 21.

Trunnion bearing 43 is a part of a reversing mechanism indicated generally by reference numeral 46 which serves to reverse the position of carrier 28 by turning it through an angle of 180° during the upward stroke of plunger 11 and carriage 23. With this in view, trunnion 43 is constituted of the inner end of a shaft 47 which turns in a bearing aperture extending through the lower end of rear plate 27 and also through a boss 48 formed thereon to lengthen the bearing surface.

In order that shaft 47 may impart rotation to reverse or invert carrier 28, an elongated key member 49 is received in a key slot 50 in the rear side of carrier 28 (Fig. 8). Key member 49 may be formed integrally with a hub portion 51 which is pinned or otherwise secured to shaft 47 and which also constitutes a spacing collar similar to member 44, to space carrier 28 from rear plate 27. It will be understood that these spacing members 44 and 45 also serve to rigidly support the sides of carrier 28 so as to maintain its axis in precise alignment with the axis of forming plunger 21.

Reversing mechanism 46 includes a stationary vertical rack bar 52 having teeth 53. Meshing with teeth 53 is a pinion gear 54 which rotates freely on a supporting shaft 55 secured at its inner end in an aperture in plates 27 somewhat above shaft 47. Shafts 55 and 47 are, therefore, both mounted on this plate 27 and are parallel to one another. Pinion 54 has on its left hand face as viewed in Fig. 4 a single laterally projecting tooth 56 which is adapted to engage successively two diametrically opposed recesses 57 in the hub 58 of a mutilated gear member 59, only one of recesses 57 being illustrated in the drawings.

Mutilated gear member 59 turns loosely on shaft 55 alongside of pinion 54, the latter being biased towards gear member 59 by means of a coil spring 60 on the outer portion of shaft 55 between pinion 54 and the head of this shaft. Consequently, pinion 54 turns ineffectively on shaft 55 during the downward stroke of carriage 23, tooth 56 being urged against the face of hub 58 by the pressure of coil spring 60. At or slightly before the end of the down-stroke, tooth 56 slips into recess 57 so that on the up-stroke it engages the wall of this recess which is parallel to the face of tooth 56 and imparts rotary movement to hub 58 and gear 59.

Gear 59 is provided with two sections of gear teeth 61 and 62 (Fig. 5), the teeth being interrupted between these two sections. The number of teeth in each of these sections corresponds with half the number of teeth in a pinion gear 63 with which they cooperate, gear 63 being fixed on the outer portion of shaft 47. Adjacent mutilated gear 59 and pinion 63 are inter-engaging locking plates 64, 65. Plate 61 is provided with two convex locking surfaces 66 and 67 disposed intermediate the two sections of gear teeth 61 and 62 and consequently diametrically opposite

one another. Plate 65 has two concave locking surfaces 68 and 69. It will be understood that locking plates 64 and 65 are secured in any suitable manner to the sides of their respective gears.

The arrangement of the construction just described is such that upon each upward stroke of carriage 23 the rotation of pinion 54 caused by its engagement with teeth 53 of the stationary rack drives hub 58 and mutilated gear 59 through one-half a revolution. During the first part of this movement one of the locking surfaces, for example, surface 67 (Fig. 5) is turned sufficiently to release locking surface 68 of plate 65. Thereupon the teeth of one of the mutilated gear sections, for example teeth 62, enter into engagement with the teeth of pinion 63 and rotate it through one-half a revolution, whereupon locking surface 66 of plate 64 engages the opposite concave locking surface 69 of plate 65. The parts remain in such locked position throughout the following downstroke of carriage 23 and until the commencement of the next upstroke of the carriage.

Figs. 12 through 16 illustrate two examples of the type of ornamentation device produced by and applied to fabric by the present machine. Figs. 12 through 14 show a device for securing ornamental stones to the fabric, while Figs. 15 and 16 show one form of nailhead. Fig. 14 shows in plan view a blank 70 for the device 71 shown in plan view in Fig. 12 and in side elevation in Fig. 13. In Figs. 12 and 13 the prongs 74 of the ornamentation device 71 have been bent substantially at right angles to the body of the device, in which position they penetrate the fabric and are then crimped or bent inwardly as shown in Fig. 10 around the crown of an ornamental stone 75 so as to engage the outer facets thereof and hold the stone in place on the surface of the fabric which is indicated by numeral 76.

Fig. 15 shows a blank 72 for the nailhead and in Fig. 16 the nailhead is shown in side elevation in condition to be applied to the fabric. In Fig. 18 the prongs which are indicated by numeral 77 have penetrated to the rear surface of the fabric and been bent flat against this surface in order to secure the nailhead in position.

When machine is used for fabricating and applying the ornamentation devices 71 and ornamental stones 75 to the fabric the forming and fashioning punch 21, having a comparatively blunt fashioning surface 78 (Fig. 10) is employed. When it is used for making and applying nailheads 73, punch member 21 is replaced by a punch member such, for example, as indicated by numeral 21m in Fig. 17 having a fashioning surface 79 which is substantially hemispherical, but which may have any suitable shape depending upon the character of the nailhead which it is desired to form.

The ornamentation devices 71 and 73 are fabricated from a strip 80 (Figs. 1-5) of suitable material, usually metal, of comparatively thin gauge. This strip is coiled on a magazine roll (not shown) which is arranged to rotate freely on a suitable supporting shaft (also not shown) and which may either be stationary or be mounted on vertical reciprocating carriage 23. Strip 80 is fed through a small rectangular channel just enough larger than the strip itself to allow the strip to move freely. This channel is formed as a groove in the bottom of die support 30 immediately above the surface of blanking die 25 and extends from side to side of carriage 23. Strip 80 is fed or pulled through the channel

just described by means of feeding mechanism mounted on carriage 23 and indicated generally by reference numeral 81 (Figs. 1 and 2) to be described in detail later.

The ornamentation devices are fabricated by mechanism mounted on vertically reciprocating carriage 23 by action which takes place after the carriage 23 has reached the lower end of its stroke where nuts 36 have engaged bosses 18 of the frame. At this point, the relative movement between plunger 11 carrying punch member 21 and carriage 23 commences, plunger 11 continuing to move downwardly while carriage 23 remains stationary.

The mechanism for actuating sleeve type blanking punch 24 includes two triangular plates 82 mounted on a pivot pin 83 which passes through enlargement 33 on the shaft 20 of punch member 12 (Figs. 1 through 3), one plate disposed on each side of the enlargement. At the outer corners of triangular plates 82 are two cam lever actuating pins 84 which extend between the two plates 82 as shown in Fig. 3. These pins 84 actuate simultaneously two cam levers 85 which are disposed centrally between triangular plates 82 and which are pivoted on pins 86 (Figs. 1, 4 and 5) in blocks 29 of carriage 23. As shown particularly in Fig. 5 the lower ends of levers 85 are received within recesses 87 milled in the upper and inner surfaces of blocks 29.

Each of levers 85 has a cam slot (Figs. 1 and 2) having a vertical portion and an inclined portion inclined upwardly towards the center of carriage 23. On the lower portions of levers 85 opposite pivots 86 are two inwardly directed projections 88 which engage closely fitting grooves in a flanged head 89 provided at the upper end of blanking punch 24. Punch 24 moves vertically in a guiding aperture 90 at the center of punch guide and die support 30.

A blank 70 is punched out of strip 80 during the first slight downward movement of plunger 11 relative to carriage 23, that is immediately after the nuts 36 contact bosses 18 and stop the downward movement of carriage 23. During this short movement the two lever actuating pins 84 carried by triangular plates 82 move downwardly in the inclined portions of the cam slots from the position shown in Fig. 1 to the position shown in Fig. 2, where pins 84 enter the upright portions of these slots. During this short movement of pins 84 levers 85 are rocked about their pivots 86 from the position shown in Fig. 1 to the upright position of Fig. 2, thereby driving the lower end of blanking punch 24 through the material of strip 80 and below the upper surface of blanking die 25 (Fig. 5).

This blanks out the ornamentation device forming a blank 70 which remains in blanking die 25 at about the position shown in Fig. 5. Blanketing punch 24 does not descend below this position relative to die 25 because during the continued downward movement of plunger 11 the two lever actuating pins 84 move in the longer upright portions of lever slots 88 which are now parallel with the path of movement of the plunger.

During such continued downward movement of plunger 11, the lower end of punch 21 contacts blank 70 and forces it downward from its position in blanking die 25 through the bending die 26, the upper edges of which are rounded as shown in Figs. 5 and 4 so as to cause the prongs 74 of blank 70 to be bent upwardly at substantially right angles to the body of the blank as shown

in Fig. 13. Punch 21 moves the blank through bending die 26 and into one of two bores 91, 91 (Fig. 10) which are located at the opposite ends of reversing carrier 28, bringing the now partially fabricated device 71 with its bent-up prongs 74 into contact with the surface of a shiftable forming or fashioning die 92 and pushing die 92 downwardly to the position shown in Fig. 10.

The two bores 91 at the opposite ends of the reversing carrier are arranged in axial alignment with one another and constitute mouth portions of an opening which extends from end to end of carrier 28, each mouth portion containing a shiftable die 92. These two dies are exactly alike and each is provided with an enlarged collar portion 93 and beyond this a stem portion 94 of considerably reduced diameter which terminates at about the center of carrier 28. The inner ends of stem portions 94 are in contact with one another so that when the upper die 92 is pushed downwardly by punch 21 it in turn forces the lower die 92 downwardly so as to bring its lower end substantially flush with the end of its bore 91. The two stem portions 94 have a pair of spaced circular grooves 95 with which spring-biased balls 96 cooperate to maintain the two die members 92 in either of two positions, namely, their upper position or their lower position.

The body of reversing carrier 28 is a substantially cubical steel block 97 (Figs. 8-10), two opposite sides of which contain aligned cylindrical recesses to receive trunnions 42 and 43. At right angles to the axis of these trunnion recesses are two integral annular extensions 98 which are in axial alignment with one another and which are provided with cylindrical bores 99 larger than bores 91 to receive the enlarged collar portions 93 of die members 92. Bores 91 are in two conical shaped members 100 which fit nicely over annular extensions 98 and have shoulders 101 at their outer ends. At the inner ends of bores 99 on the interior of annular extensions 98 are shoulders 102 of substantial width, against which the inner surfaces of collar portions 93 are adapted to seat when one of the dies 92 is forced downwardly by punch member 21 carrying the partially fabricated ornamentation blank 70 ahead of it to the position in upper bore 91 shown in Fig. 10.

When the parts reach the position shown in Fig. 10 device 71 is not completely formed but only roughed out, as will be seen from the fact that the surfaces of the body of the device do not make contact with the surfaces of the punch and die throughout. Punch 21, however, has not quite reached the bottom of its stroke, and during its final downward movement the reaction of shoulder 102 against the inner surface of collar 92 firmly supports die 92 and causes the body of ornamentation device 71 to be compressed between the punch and die (Fig. 11), thereby "forming" or "fashioning" it accurately to the punch and die surfaces.

Because of this the surface of the body portion of ornamentation device 71 can be shaped to conform closely to the shape of the bottom of the ornamental stone 75 which it is to hold in place on the fabric. For example as shown in Figs. 11 and 12 device 71 has a substantially flat central portion 110 to fit the flat base of stone 75, and an annular dished portion 111 surrounding central portion 110 to correspond to the sloping portion of the stone beneath its crown. Accurate fitting of the attaching device 71 to the

stone produces a better appearing finished fabric and more secure attachment.

When the machine is producing and attaching nailheads 72 the forming or fashioning operation above described gives the nailheads a smoother and more uniform surface, resulting in a better appearing decorated fabric, as well as firmer attachment.

The two conical members 100 of reversing carrier 28 are held in place by means of a pair of retaining bars 103 (Figs. 8 and 9) which are secured to the sides of body 97 of the carrier by means such as the screws shown, and each bar has at its opposite ends a tongue 104 which fits into a corresponding groove in the base of one of the conical members 100.

In describing the operation of the machine in applying an ornamentation device 71 and stone 75 to fabric it will be assumed that the lower bore 91 of reversible carrier 28 contains an ornamentation device fabricated on a previous stroke of plunger 11. When the carriage 23 reaches the bottom of its stroke, as determined by the contact of nuts 36 with bosses 18, the lower end of carrier 28 has descended to cooperating position with the work support, constituted of member 108 (described below) and the upper end of lower plunger 14, and as above mentioned, is substantially in contact with the fabric 76 to which the ornamentation devices and ornamental stones are attached. The proper position of carrier 28 may be obtained by adjusting nuts 36.

The rhinestones or other ornamental stones are contained in a hopper 105 of any suitable construction and which includes a feeding mechanism not shown in detail but operating by means of a belt (not shown) trained over a pulley 106. It causes the stones to be fed in a single row along a tube, or guide channel, 107, the lower end of which communicates with the interior of a combined work support and anvil guiding member 108 which is fixed to the base 2 of the machine. The stones are delivered in inverted position to the interior guide 108 within which the upper end of lower plunger 14 reciprocates.

A single stone is received on the upper end of lower plunger 14 while it is at the lower end of its stroke (somewhat below the position shown in Fig. 4) and below the opening of channel 107 into the interior of guide 108. The upper end of plunger 14 serves both to raise the stone from the position shown in Fig. 4 to that shown in Figs. 2, 3 and 10, and it serves also as an anvil or crimping surface to turn the ends of prongs 74 over the face of the stone.

Since the stone on the upper end of plunger 14 may not be in registry with the uncrimped prongs 74 (Fig. 4) means are provided for bringing about proper registry. For this purpose guide member 108 is provided with four vertical ribs 109 (Figs. 4, 7 and 10), the lower ends of which are rounded so that they may serve as cams to center the stone with respect to the prongs as the stone is raised by plunger 14. The sides of plunger 14 have vertical channels to receive ribs 109.

Continuing the description of the operation of applying an ornamentation device 71 and stone 75, the previously fabricated ornamentation device 71 is in the lower mouth portion or bore 91 of reversible carrier 28 (Fig. 4), the carrier die means including the two die members 92 being in their uppermost position as shown in that figure. The prongs of device 71 are directed downwardly. A stone 75 is on the upper end of

lower plunger 14 which is rising. The bottom of punch member 21 however has not yet contacted ornamentation device blank 70 within bending die 26.

At the top of the stroke of lower plunger 14, it raises the stone 75 against the underside of fabric 76 (Fig. 10), and main plunger 11 pushes punch 21 into the upper end of carrier 28, inserting the partially completed ornamentation device 71 in the upper mouth portion or bore 91 and forcing die means 92, 92 downward. This ejects the previously formed ornamentation device 71 from lower bore 91 and forces its prongs 74 against the crimping surface of the upper end of lower plunger 14 (Figs. 7 and 10) thereby crimping them around the stone 75 as shown in Fig. 10.

The arrangement is such that only a limited crimping pressure can be applied to lower ornamentation device 71 and stone 75 within it. Otherwise the stone might be cracked. This pressure can be regulated by adjusting nuts 36. The "forming" or "fashioning" of the ornamentation device 71 in the upper bore 91 takes place after the crimping operation and after enlargement 93 of upper die 92 seats solidly against shoulder 102 of carrier 28. Then punch 21 descends slightly further, as shown in Fig. 11, to compress the upper ornamentation device 71. It will be understood that on the up-stroke of main plunger 11, reversing mechanism 46 (Figs. 4-6) operates to invert reversible carrier 28 placing the newly completed ornamentation device at the bottom of the carrier ready for application to the fabric.

When applying nailheads 73 (Figs. 15-18) punch member 21m replaces punch 21 and if desired, although not necessary, a stationary crimping or anvil member 14m (Fig. 19) may be used in place of lower reciprocating plunger 14. It may be secured in fixed position in guide member or work support 108 by means of a removable pin 112, or in any other suitable manner.

It will be understood that punches 21 and 21m may be replaced with other of different sizes to make any desired size of ornamentation device 71 or 73. When changing the size of these punch members a new reversible carrier 28 is also installed having die members 92 to correspond.

The feeding forward of strip 80 from which the ornamentation devices are punched takes place during the up-stroke of main plunger 11. Feeding mechanism 81 is mounted on the reciprocating carriage 23 (Figs. 1 and 2). After emerging from its guiding channel through carriage 23, strip 80 passes around a friction feed roller 113 which rotates on a stud 114 projecting from the side of a bracket plate 115. This bracket is bolted on the rear of carriage 23 (Fig. 3).

After making a half turn around feed roller 113 strip 80 passes between it and a cooperating pressure roll 116 and then onto a take-up roll (not shown).

Pressure roll 116 rotates on a stud which is carried on an arm 117, whose lower end is pivoted at 118. A tension spring 119 is attached to the upper end of arm 117 to bias pressure roll 116 against strip 80 and feed roller 113.

Feed roller 113 is actuated by a lever 120 loosely pivoted on stud 114 and operatively connected to feed roller 113 by means of a one-way clutch 121 which may be of the ball type and arranged to rotate roller 113 in the clock-wise direction only. The free end of lever 120 is pivoted at 122 to the lower end of a link 123 whose upper end is con-

nected to a block 124 (Fig. 3) having a pivot 125 (Fig. 2) fixed to the rear side of one of the frame bosses 18.

During reciprocation of carriage 23 link 123 swings slightly about pivot 125 and actuating lever 120 rocks from about the position of Fig. 1 to that of Fig. 2. The length of link 123 is adjustable to vary the angular movement imparted to feed roller 113 during each up-stroke of carriage 23 so that the amount of feed of strip 89 may be correctly adjusted. This is done by tapping the lower end of link 123 into a clevis 126 (Fig. 3) and providing a lock nut 127. To prevent damage to the feeding mechanism in case of jamming the upper end of link 123 slides in an aperture in block 124 and is yieldable in one direction through the presence of a coil spring 128.

Although the invention has been set forth through the description in detail of one form of its mechanical expression, by way of example, it will be understood that it can be embodied in other forms, and, consequently, it is intended that the scope of the invention shall extend to the boundaries established by the appended claims.

I claim:

1. In a machine for applying ornamentation devices to fabric, a reciprocating plunger and a reciprocating carriage actuated thereby to reciprocate with the plunger during part of each stroke, the plunger moving relatively to the carriage during the remainder of the stroke, a reversible carrier mounted on said carriage for receiving and inverting ornamentation devices, a work support including a crimping tool, said reversible carrier being advanced to cooperating position with said work support by the reciprocation of said plunger, said reversible carrier having an opening extending from end to end thereof with a mouth portion at each end adapted to receive and hold a partially fabricated ornamentation device, die means longitudinally shiftable in said opening having a die within each of said mouth portions, punch means operated by said movement of the plunger relative to the carriage for punching out an ornamentation device and bending the prongs thereof and moving the same into one of the said mouth portions to engage the die therein and shift said die means to cause the ejection of a previously formed ornamentation device from the opposite mouth portion causing the prongs thereof to penetrate the fabric on the work holder and forcing them into engagement with said crimping tool, and means within said opening to arrest the movement of said die means to cause said first mentioned ornamentation device to be compressed by the said punch and die to fashion the same.

2. In a machine for applying ornamentation devices to fabric, a reciprocating main plunger, a reciprocating carriage actuated thereby to reciprocate with the plunger during part of each stroke, said plunger moving relatively to the

carriage during the remainder of the stroke, a reversible carrier mounted on said carriage having an opening extending from end to end thereof with a mouth portion at each end of said opening adapted to receive a partially complete ornamentation device, a plunger in said opening shiftable by the insertion of an ornamentation device at one end to cause the ejection of a second ornamentation device previously inserted at the opposite end, a work support including a crimping tool, said reversible carrier being advanced by said main plunger to place one end thereof in cooperating position with said work support, a punch operated by said movement of the main plunger relative to the carriage to blank out an ornamentation device, and a second punch similarly and subsequently operated to bend the prongs of said device to push it into one of said mouth portions.

3. In a machine for applying ornamentation devices to fabric, a work support including a crimping tool, a reciprocating plunger and a reciprocating carriage actuated thereby to reciprocate with respect to said work support, a reversible carrier mounted on said carriage for receiving and inverting ornamentation devices, adjustable means for arresting the movement of said carriage when said reversible carrier has advanced to cooperating position with said work support, means within said carrier for ejecting an ornamentation device therefrom causing the prongs thereof to penetrate the fabric on said work support and forcing them into engagement with said crimping tool, and means for actuating said ejecting means.

4. In a machine for applying ornamentation devices to fabric, a reversible carrier having an opening extending from end to end thereof with a mouth portion at each end adapted to receive and hold a partially fabricated ornamentation device, die means longitudinally shiftable in said opening having a die within each of said mouth portions, a reciprocating punch member adapted to move a partially fabricated ornamentation device into one of the said mouth portions to engage the die therein and shift said die means to cause the ejection of a previously formed ornamentation device from the opposite mouth portion of said carrier, and means within said opening to arrest the movement of said die means to cause said first mentioned ornamentation device to be compressed between said punch and die.

CESAR BUSTAMANTE.
